Primary Examiner — Philip S Hyder(74) *Attorney, Agent, or Firm* — Rocklaw PLLC; Michael T. Fluhler(57) **CLAIM**

The ornamental design for an untwist tool, as shown and described.

DESCRIPTION

FIG. 1 is a front isometric view of an untwist tool showing our new design;

FIG. 2 is a rear isometric view thereof;

FIG. 3 is side view thereof;

FIG. 4 is a front view thereof; and,

FIG. 5 is a rear view thereof.

The broken lines illustrate boundaries or aspects of the untwist tool in which the design is embodied that form no part of the claimed design.

1 Claim, 4 Drawing Sheets(56)
